UNITED STATES PATENT OFFICE

HERBERT SCHOTTE, OF BERLIN-REINICKENDORF, GERMANY, ASSIGNOR TO SCHERING-KAHLBAM A. G., OF BERLIN, GERMANY

METHOD OF PRODUCING SUBSTITUTED GUANIDINES

No Drawing. Application filed September 13, 1928, Serial No. 305,863, and in Germany September 12, 1927.

My invention refers to the production of guanidine derivatives and more especially to a method of producing substituted guanidines.

Whereas cyanamide and monoalkyl cyanamides react with amine salts very favourably particularly when working in very concentrated solution disubstituted cyanamides do not react favourably with amines or amine salts. (Compare Lecher & Demmler Zeitschrift für physiologische Chemie 167,170 (1927)).

By the present invention the reaction between dialkyl cyanamides and amine salts is caused to take place very smoothly, and with many derivatives it is not even necessary to increase the temperature.

The process of manufacture according to the invention is by bringing a dialkyl cyanamide into reaction with an amine salt in the presence of a free amine.

The reason for the smooth and favourable reaction cannot yet be definitely explained, possibly an intermediate product of the following constitution is produced:

wherein R is an alkyl and X an acid radical which reacts further with the amine.

The following formula shows the structure of the guanidine nucleus,

The following examples illustrate the invention.

Example 1

5 parts of diethyl cyanamide heated with 45 6.5 parts of aniline hydrochloride and 3 parts of aniline for 10 hours to 100° C. give alpha, alpha-diethyl-beta-phenyl guanidine which is obtained as the oily base by steam distillation of the deposit after rendering alkaline or 50 which can be separated as the picrate of melt-

ing point 118° C. Aniline itself also reacts with dialkyl cyanamide without the addition of hydrochloride. The yields of guanidine are however better in the first case.

55

Example 2

2.7 parts of diethyl cyanamide, 5 parts of isoamylamine and 7 parts of isoamylamine hydrochloride give on long standing or after heating for about one hour to 100° C. the 60 alpha, alpha-diethyl-beta-isoamyl guanidine, the hydrohalogen acid salts of which are easily soluble in water and the picrate of which melts at 120° C.

65

Example 3

3 parts of dimethyl cyanamide treated in the same manner as in Example 2 (with four parts of amine and five parts of hydrochloride) give alpha, alpha-dimethyl-beta-isoamyl-guanidine. The picrate melts at 70 104° C.

70

Example 4

2 parts of dimethyl cyanamide, 1.9 parts of 75 ethylamine and 3.5 parts of ethylamine hydrochloride give after standing for some time the alpha, alpha-dimethyl-beta-ethyl guanidine the picrate of which melts at 152° C.

75

Various changes may be made in the details disclosed in the foregoing specification without departing from the invention or sacrificing the advantages thereof.

80

I claim:

The method of producing substituted guanidines by treating a dialkyl cyanamide with a salt of an amine which has at least one hydrogen atom attached to the nitrogen atom, in the presence of the corresponding free amine.
